Assignee to John S. Rathbone, of same place
Letter Patent No. 41 dated May 7 1861.
No. 1406

The schedule referred to in these Letters Patent and making part of the same.

Be it known that I Samuel W. Gibbs, of the City of Albany, State of New York, have produced a new and original ornamental design for the plates of a Cooking Stove, known as the Western home, and I declare the accompanying drawings forming part of this specification to be an accurate representation of the said plates of the stove with their ornaments; and that what I claim as my production and desire to secure by Letters Patent is the combination and arrangement of figures and forms represented in the said drawings, forming together the ornamental design for the plates of a Cooking Stove.
